BRASSIERE

Jack J. Locascio, Bayonne, N.J., assignor to International Playtex Corporation

Filed May 14, 1973, Ser. No. 359,933

Term of patent 14 years

Int. Cl. D2—01

U.S. Cl. D2—24

FIG. 1

FIG. 1 is a perspective front view of a brassiere showing my new design, the side and back panels thereof being conventional; and

FIG. 2 is an inside plan view.

I claim:

The ornamental design for a brassiere, substantially as shown and described
